UNITED STATES PATENT OFFICE.

CHARLES HAMILTON PAJEAU, OF EVANSTON, ILLINOIS, ASSIGNOR TO THE TOY
TINKERS, INC., A CORPORATION OF ILLINOIS.

DESIGN FOR A WHEELED TOY.

Application filed August 1, 1924. Serial No. 10,339. Term of patent 14 years.

To all whom it may concern:

Be it known that I, CHARLES HAMILTON PAJEAU, a citizen of the United States, residing at Evanston, in the county of Cook and State of Illinois, have invented a new, original, and ornamental Design for a Wheeled Toy, of which the following is a specification, reference being had to the accompanying drawings, forming part thereof.

In the drawings, Fig. 1 is an elevation of a wheeled toy, showing my new design.

Fig. 2 is a plan view of the same toy in another position.

I claim:

The ornamental design for a wheeled toy as shown.

CHARLES HAMILTON PAJEAU.
